UNITED STATES PATENT OFFICE.

THOMAS MOORE, OF WESTERLY, RHODE ISLAND.

DESIGN FOR ELASTIC WOVEN FABRIC.

Application filed August 4, 1923. Serial No. 6,942. Term of patent 14 years.

To all whom it may concern:

Be it known that I, THOMAS MOORE, a citizen of the United States, residing at Westerly, in the county of Washington, State of Rhode Island, have invented a certain new, original, and ornamental Design for Elastic Woven Fabric, of which the following is a specification, reference being had therein to the accompanying drawing.

The drawing is a face view of a portion of elastic woven fabric, showing my new design.

I claim:

The ornamental design for elastic woven fabric, as shown.

THOMAS MOORE.
